The ornamental design for a baseball training aid with positionable target, as shown and described.

DESCRIPTION

FIG. 1 is a front view showing my new design for a baseball training aid with positionable target;

FIG. 2 is a front view showing a second embodiment of my new design;
FIG. 3 is a front view showing a third embodiment of my new design;
FIG. 4 is a front view showing a fourth embodiment of my new design;
FIG. 5 is a front view showing a fifth embodiment of my new design;
FIG. 6 is a front view showing a sixth embodiment of my new design;
FIG. 7 is a front view showing a seventh embodiment of my new design;
FIG. 8 is a front view showing an eighth embodiment of my new design;
FIG. 9 is a front view showing a ninth embodiment of my new design;
FIG. 10 is a front view showing a tenth embodiment of my new design;
FIG. 11 is a front view showing an eleventh embodiment of my new design;
FIG. 12 is a front view showing a twelfth embodiment of my new design;
FIG. 13 is a front view showing a thirteenth embodiment of my new design;
FIG. 14 is a front view showing a fourteenth embodiment of my new design;
FIG. 15 is a front view showing a fifteenth embodiment of my new design;
FIG. 16 is a front view showing the positionable target and support panel in FIGS. 1-15 in a separated state;
FIG. 17 is a rear view of the support panel shown in FIG. 16;
FIG. 18 is a right side view of FIG. 17, the left side view being identical thereto;
